DEVICE FOR DISTRIBUTING AIR

Jost Sassenberg, Cologne, Germany, assignor to
Franz J. Kurth, Cologne-Dellbruck, GermanyApplication November 23, 1932, Serial No.
643,959, and in Germany November 28, 1931

3 Claims. (Cl. 98—40)

This invention relates to improvements in devices for distributing air, for example ventilating devices, and is concerned with devices of the type comprising a number of co-axial truncated 5 pyramidal (for example conical) partitions or shells which are spaced apart and arranged with their smaller ends all directed towards the same end of the device thus providing a number of separate air passages.

10 A sensation of draught occurs in a room when air is introduced into the room at a velocity which is too high to be comfortable. In the art of ventilation, therefore, efforts are made to annul the velocity of an air current introduced into a room 15 immediately at its place of inlet, or to reduce the velocity to such an extent as to avoid draughts. This can be accomplished by means of ventilating devices of the type with which the invention is concerned mounted in front of the air inlet 20 into the room. Such ventilating devices divide the incoming air current into a number of separate currents, and have comprised partitions the lateral walls of which form with the axis of the device obtuse angles in the direction of flow of the 25 air current and which provide air passages of gradually increasing cross-section outwardly. Other ventilating devices are known which deflect the air current in its full cross-section in all directions. A device is also known whereby the 30 incoming air current is divided, by means of perforated circular plates disposed at right angles to the axis of that current, into separate currents which are situated in front of one another and are deflected at right angles to the said axis. 35 Deflection at right angles to the direction of flow of the incoming air current has the disadvantage of considerably increasing the resistance and therefore of operating uneconomically, due to the increased consumption of power.

40 The object of the present invention is to provide improved air-distributing devices of the aforesaid type.

With this object in view, the invention provides an air-distributing device of the type described wherein the partitions are located in front of one another in the direction of the axis of the device, in contradistinction to the known devices of this type in which the partitions lie one within another.

50 The lateral walls of the partitions may be parallel to one another and form obtuse angles with the axis of the device in the direction of flow of the air current, in which case these angles are equal to one another.

55 Alternatively, the lateral walls of the partitions

may form with the axis of the device obtuse angles in the direction of flow of the air current, the magnitude of which angles increases from the inner to the outer end of the device so as to provide between each two partitions an air passage of gradually increasing cross-section from its inner to its outer end. By the inner end of the device is meant that end which is or can be connected to a pipe through which air enters the device, or leaves the device if it is used as an air outlet device.

60 Preferably the smaller, inner ends and also the larger, outer ends of the partitions progressively decrease in diameter from the inner to the outer end of the device.

70 Two embodiments of the invention suitable for ventilating purposes will now be described, as examples, with reference to the accompanying drawing, in which:—

75 Figure 1 is a diagrammatic section of one construction and

Figure 2 is a similar view of the other construction.

80 Like reference characters indicate like parts throughout.

The construction shown in Figure 1 comprises a pipe E and a number of truncated conical partitions a to f situated in front of one another with their smaller ends directed towards the pipe E but out of the plane of the adjacent end of the 85 next partition on the side of that plane remote from the pipe E. The partition a is rigidly secured to the pipe E, while the other partitions are connected to the partition a and to one another by a plurality of retaining elements g. Retaining elements may also be employed at the inner edges of the partitions if the size of the distributor renders that desirable. The lateral walls of the partitions a to f are parallel to one another and they form, with the axis h—h¹—h² of 90 the device, obtuse angles α^1 to α^6 which are equal to one another. The smaller, inner ends and also the larger, outer ends of the partitions are of gradually decreasing diameter from the partition a to the partition f. It is not essential for the partitions a to f to be at the same distance from one another.

100 Assuming that air enters the device through the pipe E, it first encounters the inner edge of the partition b and an annular portion of the air current is deflected obliquely downwards by the partition b. The residue of the incoming air current then meets the inner edge of the partition c where another annular portion thereof is deflected 105 and so on until only a small residue of the incom- 110

ing air current is left which flows through the small opening in the inner end of the partition *f*. The separate annular currents which are thus deflected obliquely downwards by the partitions 5 *a* to *f* flow into the room all round the device. It will be appreciated that, due to the division of the incoming air current into separate currents and to the adhesion of those currents to the partitions, the velocity of the air entering the room 10 is so small that it is not felt as a draught, and also that, due to the fact that the separate currents are deflected from the main incoming current at an obtuse angle and not at right angles thereto, there is only a slight increase in resist- 15 anse.

In the construction shown in Figure 2, the distance between each pair of partitions is greater at their outer edges than at their inner edges. The angles β^1 to β^6 formed by the partitions and 20 the axis $h-h^1-h^2$ of the device increase as the distance of the partitions from the inlet pipe *E* increases, and as adjacent partitions diverge outwardly, the velocity of the separate currents flowing between them is reduced to a greater extent 25 than in the device according to Figure 1.

As in the case of the construction illustrated in Figure 1, the smaller, inner ends and also the larger, outer ends of the partitions progressively decrease in diameter towards the outer end of 30 the device; i. e., from the partition *a* to the partition *f*. Because of the progressively decreasing diameter of the inner ends of the partitions successive annular portions of the air or gas stream are deflected outwardly by the successive 35 partitions as heretofore stated, while because of the progressively decreasing diameters of the outer ends of the partitions the air or gas is liberated at points progressively closer to the axis of the device toward its outer end and a wider and 40 therefore better distribution of the air or gas is obtained than would be obtained if, for example, the partitions all were of the same diameter at their outer ends. Moreover, the velocity of the 45 air or gas decreases as it approaches the outer end of the device. If, therefore, the several partitions were of equal or substantially equal size, the distribution of the air or gas through the respective passageways would not be uniform, 50 assuming that the device was otherwise constructed to effect discharge of approximately equal volumes of air or gas through the respective passageways. However, because of progressively decreasing the diameters of the larger ends 55 of the partitions toward the outer end of the device, their surface areas are progressively decreased and consequently their frictional resistance to flow of the air or gas is progressively decreased, so that despite the decrease in velocity 60 of the air or gas as it reaches the successive partitions the volumetric distribution through the

respective passageways is or may be substantially uniform. Again, because of progressively decreasing the diameters of the larger ends of the partitions toward the outer end of the device, the device may be constructed of much shorter length using any given number of partitions than 80 would be possible if the partitions all were of equal diameter at their larger, outer ends.

Preferably, a device according to Figure 1 will be used when the velocity of the incoming air current is low, and a device according to Figure 2 will be employed when that velocity is high. 85

The device shown in Figure 1 has the advantage that it can be more economically manufactured than that shown in Figure 2 because all the partitions are of the same inclination and can be made from the same pattern. 90

Both devices can also be employed for extracting air from a room, in which case the pipe *E* will be connected to the air outlet. 95

Having fully described my invention, what I claim as new, and desire to secure by Letters Patent, is—

1. A device of the character described comprising a series of outwardly flaring truncated hollow members open at their ends and disposed with their axes in substantially the same straight line and with their smaller ends all facing the inner end of the device, said members being successively spaced outwardly each entirely in front 100 of the preceding member, and the obtuse angles between the surfaces of the members and the axis of the device progressively increasing toward the outer end of the device. 105

2. A device of the character described comprising a series of outwardly flaring truncated hollow members open at their ends and disposed with their axes in substantially the same straight line and with their smaller ends all facing the inner end of the device, said members being successively spaced outwardly each entirely in front 110 of the preceding member, said members being of progressively decreasing diameters both at their inner and their outer ends toward the outer 115 end of the device, and the obtuse angles between the surfaces of the members and the axis of the device progressively increasing toward the outer end of the device. 120

3. A device of the character described comprising a series of outwardly flaring truncated hollow members open at their ends and disposed with their axes in substantially the same straight line and with their smaller ends all facing the inlet end of the device, said members being successively spaced outwardly each entirely in front 125 of the preceding member, and the larger outer ends of said members progressively decreasing in 130 diameter toward the outlet end of the device. 135
